Primary Examiner — Karen E Eldridge Powers*(74) Attorney, Agent, or Firm* — R. Blake Johnson; DLA Piper LLP (US)(57) **CLAIM**

The ornamental design for a glove, as shown and described.

DESCRIPTION

FIG. 1 is a perspective view of the glove;

FIG. 2 is a front elevational view of the glove;

FIG. 3 is a rear elevational view of the glove;

FIG. 4 is a left side elevational view of the glove;

FIG. 5 is a right side elevational view of the glove;

FIG. 6 is a top plan view of the glove; and,

FIG. 7 is a bottom plan view of the glove.

The broken line in FIG. 7, which defines the bounds of the claimed design, forms no part thereof.
